UNITED STATES PATENT OFFICE.

ARTHUR C. MCWILLIAMS, OF CHICAGO, ILLINOIS.

METERING PANEL-BOARD.

1,137,413.

Specification of Letters Patent. Patented Apr. 27, 1915.

Application filed April 26, 1910. Serial No. 557,535.

To all whom it may concern:

Be it known that I, ARTHUR C. MCWILLIAMS, a citizen of the United States, residing at Chicago, in the county of Cook and State of Illinois, have invented a certain new and useful Improvement in Metering Panel-Boards, of which the following is a specification.

My invention relates to metering panel boards of the general class described in my previous Patents Nos. 872,670, 920,490, 931,464 and 936,252.

Among the objects of my invention are first, to economize space, second, to reduce the liability of short circuits, third, to prevent plugging through at wrong points of intersection, fourth, to render the principle of operation of the apparatus more apparent so that a person may see at a glance what the various meter and circuit groupings are, fifth, to improve the connectors, and thus facilitate their use and their electric contact, sixth, to obtain flexibility as to fusing so that a tenant occupying large space may be provided with fuses of sufficient current carrying capacity without requiring any structural changes in the apparatus, and seventh, to prevent the small consumer from improperly increasing the fuse capacity in his circuit.

I accomplish my objects by the mechanism illustrated in the accompanying drawings, in which—

Figure 1 is a general view of the apparatus and the wiring connections. Fig. 2 shows the apparatus alone. Fig. 3 is a view partly in section showing one of the circuit bars, a group of meter bars and a detail of a suitable plug connection. The plane of section is indicated by the line 3—3 of Fig. 1. Fig. 4 is a view partly in section of a portion of one of the bus bars and a detail of a suitable plug connection. Figs. 5 and 6 are perspective views of the parts of the connectors shown at the left end of Fig. 3. Figs. 7 and 8 are perspective views of the parts of the connector shown at the left end of Fig. 4. Figs. 9 and 10 are perspective views of parts of the connectors shown assembled at the upper left portion of Fig. 3. Fig. 11 is a view of a circuit bar. Fig. 12 is a sectional view showing a modification

of the form of connection shown at the lower left portion of Fig. 3. Figs. 13 and 14 are perspective views of the parts of the connector shown in Fig. 12. Fig. 15 is a perspective view of one of the spring clips by which the fuses are removably held in place.

Similar reference characters denote similar parts throughout the several views.

In the form selected to illustrate my present invention provision is made for a three-wire system, although the principle of the apparatus applies equally well to a two-wire system. In the present arrangement the panel or base *a* consists of any suitable insulating material and is provided with a number of parallel meter bars *b*. Some of these bars are continuous, while others are formed in separate sections, insulated from each other, the purpose being to increase the number of bars which may be placed in a given space on the board and at the same time give ample range of selection as to what consumption circuits may be grouped together.

Running transverse to the meter bars are circuit bars *c* which are raised above the meter bars so as to be insulated therefrom, as shown in detail in Fig. 3. These circuit bars have a number of screw sockets formed therein, one socket for each of the bars *b*. Bus bars *d* are arranged at the top of the panel, running horizontally, and in these bus bars are formed screw sockets for receiving fuse plugs *e*. The distance between any two circuit bars is great enough to insure against any possible short-circuiting, and the same is true of the bus bars *d*, but the screw sockets formed in the circuit bars and bus bars may be, and preferably are, located as close together as structural conditions and the heads of the fuse plugs will permit. This economizes space without incurring any danger of short-circuiting. The segregation of the circuit conductors from the bus bars is of special advantage in at least two particulars; first, the operator can see at a glance which sockets form the bus connection and which form the consumption circuit connection; second, as the bus bars are in different parts of the board, the danger of short circuit is reduced to a minimum. All

the screw sockets in the bus bars are of one polarity and all in the circuit bars on a given side of the board are of one polarity, and as the different polarities are located at 5 different parts of the board, I am enabled to make the formation very compact without danger. Under ordinary circumstances the fuse plugs *e*, which are of usual standard construction, will never be disturbed but will 10 remain in the bus bars no matter what groupings of consumption circuits to meters is desired.

I will now describe the preferred manner of establishing electrical connection between 15 any given circuit bar and the desired one of the meter bars beneath it. The parts are shown in detail in Figs. 3, 9 and 10. In this form the fuse plugs *f* are of ordinary standard construction like the plugs *e*, and 20 screw into connector bushings *g*, which are of conducting material, and screw into the screw sockets formed in the circuit conductors. These bushings are provided with insulating blocks *h* which are centrally ap- 25 pertured to receive the shank of a bolt *i* and are countersunk top and bottom to receive respectively the head of bolt *i* and the contact piece *j*. In the preferred construction the head of the bolt is polygonal and the 30 piece *j* cylindrical so that the parts may be assembled by screwing piece *j* onto the shank of the bolt while the bolt itself is prevented from turning by its polygonal head. In order to take care of possible var- 35 iations in the heights of different contact bars it is desirable that the insulating block be countersunk to sufficient depth to permit vertical play of the bolt and its contact piece when the two are assembled, as illustrated 40 in Fig. 3. The construction is such that when the plug *f* is screwed into the bushing the plug will make contact on the outside with the bushing and at the center with the head of the bolt *i* and will force the bolt 45 and its connecting piece *j* down so that the latter will make electrical contact with the underlying meter bar *b*. It is desirable to provide means for locking the connector bushing in place, and this is accomplished 50 in the present construction by placing a set screw *k* arranged horizontally in the sides of the screw sockets in such position as to contact the side of the bushing and prevent the latter from being unscrewed.

55 I will next describe an advantageous form of connector for connecting the circuit bars *c* with their respective consumption circuit conductors. These parts are shown in the lower left portion of Fig. 3 and in Figs. 5 and 6. A bushing *m* of conducting material is so formed as to screw into the foot of the circuit conductor and is centrally apertured to receive the shank of a bolt *o*. Said bushing extends down through a suitable aper-

ture in the panel *a* so that the circuit wire *p*, 65 which leads from the consumption circuit may be connected at the back of the board. The end of the wire passes transversely through a nut *r* which screws onto the lower end of bolt *o*. Nut *r* is polygonal in cross 70 section and fits between the branches *m'm'* formed at the lower end of the bushing *m*, as clearly shown in Fig. 5. This formation prevents the nut *r* from rotating when the bolt *o* is screwed into it. In use, the wire *p* passes through the nut *r* from side to side 75 and is contacted by the lower end of bolt *o* when the parts are assembled as shown in Fig. 3. A finished effect is imparted by providing a cap nut *s* which screws upon the upper end of bushing *m*. An alternative form of connector for use at this point is shown in Figs. 12, 13 and 14. In this form a bushing *t* screws into the foot of the circuit bar and extends down to the board as before. Said bushing is vertically apertured and has a slot *t'* at the top through which the upper 80 end of the wire extends laterally so that it may be contacted by the washer *u* shown in perspective in Fig. 14. A nut *v* screws on 85 the bushing down to the washer *u* and makes a secure and permanent connection between the wire and the circuit bar.

The preferred manner of connecting the bus bars *d* to the proper side of the consumption circuits is shown in detail in Fig. 4. In this form a block *w* of insulating material is let into the back of the board and is recessed to receive a bolt *x* having a polygonal head which prevents the bolt from 95 rotating. Said bolt screws into a nut *y* on the top of the board which is of a sufficient height to make contact with the center of the fuse plug when the latter is in position. The head of the bolt *x* is recessed so that the 100 end of the conductor leading from the consumption circuit may be soldered into it.

In this three-wire system illustrated the positive, neutral and negative terminals 1, 2 and 3 respectively are connected with the proper supply cables and the circuit is opened and closed by a suitable switch 4. The bus bars *d* are connected to a bar 5 on the back of the board, which is connected to the neutral switch terminal 6. The positive 110 and negative switch terminals 7 and 8 are connected to the positive and negative fuse bars 9 and 10 respectively, which are of special construction to afford flexibility to the apparatus. If a tenant occupies a large suite of rooms, the current for all of which is measured in a single meter, it is obvious that he will need greater fuse capacity than the tenant occupying but a few rooms. My construction renders a large range of fusing 120 possible.

To facilitate explanation, the meters shown in Fig. 1 are lettered in capital let-

ters running from A to H. A wire from each of these meters is connected to a terminal on the panel board bearing a corresponding letter with a prime index. Let it be assumed that the meter A is assigned to the largest user of current. The terminal A' to which this meter is connected is so constructed as to accommodate three fuses A² in parallel, as shown. The other ends of the 10 fuse are electrically connected to the fuse bar 10. These fuses are of the ordinary commercial construction and are removably secured in position by means of the ordinary commercial clips such for example as shown 15 in Fig. 15. Any one, or any two, or all three of the fuses may be slipped into or out of position with the advantage that the user of meter A may be provided with any desired fuse capacity ranging from say 1 to 90 20 amperes. Fuses are usually supplied commercially in different sizes running in units from 1 to 10 and 15, 20, 25 and 30. Thus, if the user of meter A starts with a small number of rooms, the electrician will put only 25 one fuse in position to connect the terminal A' and the fuse bar 10. The capacity of this single fuse will be selected with reference to the number of lamps, fans or other translating devices expected to be used. If, 30 subsequently, the user increases his space so that he will require a fuse capacity greater than a single fuse will furnish, the electrician will add another fuse or two fuses, as may be required. The point is that the 35 terminal A' and fuse bar 10 are so constructed that any number of fuses from one to three may be employed. In boards heretofore constructed, if a single user required a fuse capacity greater than the capacity 40 that a single fuse could afford, new wiring arrangements of some kind had to be made, or else a second meter had to be called into requisition. With my construction a wide range is provided for without changing any 45 of the connections, and without requiring the user of a second meter.

There is no need of a large number of three-fuse terminals, and in the construction shown the terminals B' and C' are two-fuse terminals, and the remaining terminals which connect to fuse bar 10 are single fuse terminals. The electrician, in connecting up the suites, provides a three-fuse terminal 50 for the tenant who does, or in all probability will, require the greatest capacity, and provides a two-fuse terminal for smaller tenants, while the ordinary tenant will have but a single fuse terminal. This arrangement avoids waste of space on the board and 55 waste of material.

In the board selected to illustrate this invention there are two groups of circuit bars, the groups being arranged on opposite sides of the median line of the board. This double

grouping permits the board to be much 65 shorter than would otherwise be required. This is of great importance, for in ordinary buildings the available space for a meter closet is very limited. In this double grouping the circuit bars on one side of the board 70 are for one set of circuits, and the bars on the other side are for a different set of circuits. It may occur, however, that a single tenant will occupy rooms in different parts 75 of the building. With my board this does not prevent the metering of all the rooms upon the same meter for I form an extension 15 upon two of the meter bars lying on opposite sides of the board, as shown at the top of Figs. 1 and 2, and provide ordinary fuse 80 clips at the end adapted to receive a fuse 16. By inserting this fuse and then plugging in at the proper point, any circuit may be thrown on to the meter with the bars thus extended. In a similar manner extensions 85 17 are provided at the bottom of the board, and thus two different tenants having scattered rooms may be taken care of.

In operation, the electrician first selects the various meters to be used for the different 90 tenants and inserts the number and size of fuses required. He then proceeds to connect up a given tenant by first determining what screw socket in the circuit bar will produce the metering connection desired, 95 and then screws the connector bushing *g* into such socket and locks it in place by means of the small set screw *k*. On account of the position of this set screw it can not be removed by an unauthorized person unless the 100 latter has provided himself with a special tool, the result of which is that there is little likelihood that any unauthorized person will 105 tamper with the metering connections. The power company or building owner, therefore, has reasonable assurance that all current consumed will be registered upon the proper meter. After the bushing has once been set in place the consumption circuit 110 may be thrown into and out of service by merely screwing or unscrewing the fuse plug from said bushing. There will be but a single bushing for any given circuit bar and thus the location of the bushing will indicate to the electrician what the proper location for the fuse plug is no matter how long 115 a time has elapsed since the service to such circuit has been discontinued. Days and weeks may frequently elapse between the discontinuance and renewal of service to any 120 particular circuit but the memory of the electrician need not be relied on for the connector bushing will indicate the proper point to put the plug.

Having thus described my invention what 125 I claim as new and desire to secure by Letters Patent is:—

1. A metering panel board having a plu-

- rality of groups of fixed crossed conductors, the conductors running one way being for the meter circuits and those running across them being for the consumption circuits, 5 said conductors being adapted to be electrically connected at their points of crossing, and means for electrically energizing said conductors, all the conductors of a group being normally of the same polarity and the 10 conductors of one group being of a different polarity from the conductors of another group.
2. A metering panel board having groups of permanent crossed conductors, substantially all of the conductors of a group being of the same polarity and differing in polarity from the conductors of another group, the conductors running one way being for the meter circuits and those running across them being for the consumption circuits, 15 said conductors having means for electrically connecting them at their points of crossing, a bus bar and means for connecting it to a plurality of the said consumption circuits, said bus bar being arranged crosswise of a plurality of said groups beyond the ends thereof.
3. A metering panel board having crossed permanent conductors arranged in a plurality of groups, substantially all of the conductors of a group being of the same plurality and differing in polarity from the conductors of another group, the conductors running one way being for the meter circuits, those running across them being for the consumption circuits, means for electrically connecting said crossing conductors at the points of crossing, a bus bar extending across two or more of said groups and being 30 located slightly beyond the ends of said groups, and means for connecting said bus bar to a plurality of the consumption circuits to thereby complete the circuit through them.
4. A metering panel board having crossed permanent conductor bars arranged in a plurality of groups, substantially all of the bars of a group being of the same polarity and differing in polarity from the bars of another group, each group consisting of vertically arranged meter bars and horizontally arranged consumption circuit bars, means for electrically connecting said bars at their points of crossing, and horizontally arranged bus bars located slightly beyond the ends of the meter bars adapted to be electrically connected to the consumption circuits. 45
5. A metering panel board having stationary crossed conductors segregated into two groups substantially all of the conductors of a group being of the same polarity, and the adjacent groups being of different polarity, and said conductors being adapted 60
- to be electrically connected at their points of crossing, and a bus bar whereby the circuits may be energized.
6. A metering panel board having stationary conductors segregated into three groups each of different polarity, one group 70 of conductors constituting bus bars and each of the other groups comprising crossed permanent conductors adapted to be electrically connected at their points of crossing, the conductors running one way being for the 75 meter circuits, and those running across them being for the consumer's circuit.
7. The combination with a meter bar and a circuit bar having a screw socket, of means for connecting said bars, said connecting 80 means comprising a bushing of conducting material adapted to screw into the socket of the circuit bar, a fuse plug adapted to screw into said bushing to make contact therewith on the outside of the plug, a block of insulating material axially arranged within said bushing and a connecting element passing axially through said block and adapted to make electrical contact with the center of said fuse plug and with the adjacent meter 85 bar.
8. The combination with a meter bar and a circuit bar having a screw socket, of means connecting said bars, said connecting means comprising a bushing of conducting material adapted to screw into the socket of the circuit bar, a fuse plug adapted to screw into said bushing to make contact therewith on the outside of the plug, a block of insulating material axially arranged within said bushing and a connecting element passing axially 90 through said block and adapted to make electrical contact with the center of said fuse plug and with the adjacent meter bar, there being play in an axial direction between 95 said connecting element and said block of insulating material for accommodating circuit bars of different dimensions.
9. A metering panel board adapted for a three wire system of distribution, said board 100 having permanent parallel meter bars arranged in two groups, a set of consumption circuit bars of one polarity crossing one group of meter bars, a second set of consumption circuit bars of another polarity 105 crossing the other group of meter bars, and a bus bar spaced apart from the other bars, said bus bar being for the remaining sides of the consumption circuits, the bars of different polarities being therefore grouped from 110 each other to minimize the danger of short circuiting.
10. In a connector, the combination of a conductor, a fuse plug adapted to screw thereinto for making contact therewith on 115 the outside of said plug, a nut adapted to contact the center of said fuse plug, a bolt 120 screwing into said nut and a block of in-

sulating material through which the shank of said bolt passes, said block having a recess adapted to receive the head of said bolt and prevent rotation thereof, and the head of said bolt being adapted to make electrical contact with the remaining conductor.

In witness whereof, I have hereunto sub-

scribed my name in the presence of two witnesses.

ARTHUR C. McWILLIAMS.
